PAPER FEED MECHANISM

John Mueller, North Bergen, N. J., assignor to
Remington Rand Inc., Buffalo, N. Y., a corporation of Delaware

Application October 15, 1941, Serial No. 415,078

2 Claims. (Cl. 197—127)

This invention relates to the feed mechanisms of machines adapted to handle forms or sheets, and in particular to the drive for the feed mechanisms of record controlled accounting or similar business machines.

The invention has for its object to feed forms or sheets of paper from a given source to any desired position, a distance which may be varied by the operator to suit different conditions.

Although a variable length form feed can be used in many types of machine, one use and one construction in particular will be selected to illustrate the invention. It will be considered in connection with a Powers tabulating machine, and in a like manner was shown, but not fully described, in my Patent No. 2,274,088, issued February 24, 1942, of which this is a continuation in part. When thus employed in a tabulator, the present invention is in the form of an adjustable long feed mechanism.

Under ordinary circumstances, forms or sheets of paper are fed by a picker mechanism from a magazine to the initial feed rollers of a long feed mechanism, the other feed rollers of which convey the sheets to a definite printing position on the platen. The present drive mechanism is adjustable, however, so as to prolong or decrease the length of the long feed operation.

A principal feature of the invention, therefore, is a simple driving means which may be adjusted to vary the length of the long feed.

Other objects and structural details of the invention will be apparent from the following description when read in connection with the accompanying drawings, wherein

Fig. 1 is a side elevation of the head unit of a tabulator, showing the adjustable long feed mechanism;

Fig. 2 is a detail side elevation with parts broken away showing the cooperation of parts of the long feed mechanism with the operating gear of the platen and the feed roll mechanism;

Fig. 3 is a detail end view of Fig. 2; and

Fig. 4 shows two bills of a utility company, illustrating various lengths of long feed operation for which the present invention may be utilized.

In considering the present device in connection with a Powers tabulating machine, only such parts of the latter are shown as to give a proper understanding of the invention as used in this instance. It will be seen, then, from Fig. 1, that a retainer 100 is provided from which a picker mechanism, generally indicated at 103, feeds single sheets of paper one at a time to

the initial feed rollers (not shown) of the long feed mechanism. The initial and other feed rollers (also not shown) of the long feed mechanism, and the platen 21, are driven by a system of cooperating gears 65—68, inclusive, and 202—205, inclusive, from a drive gear 200, mounted on a stub shaft 201. It is the extent of rotation of gear 200 which determines the length of the long feed, and it is the means for driving gear 200 which constitutes the present invention

The gear 200, and consequently the feed rollers and the platen, are driven from main operating shaft 37 of the tabulator. A gear 213 (Fig. 1) is loosely mounted on the shaft 37, and is provided with a hub upon which is pivotally attached a spring-pressed dog 215. The dog 215 has a tooth 216 adapted to engage a notch 217 in a clutch sleeve 218 fixed on the shaft 37, and has a tail 221 by the cooperation of which, with a pivoted latch 219, the dog 215 is ordinarily held out of engagement with clutch sleeve 218 against the action of its spring. To permit dog 215 to engage sleeve 218 and thus cause the gear 213 to be rotated, latch 219 must be tripped, and to accomplish this linkage 221—224 is provided to connect latch 219 with the front total shaft 220. When a change of designation is sensed in the card sensing chamber, the total taking control mechanism operates, rocking shaft 220 counterclockwise, thus actuating the connecting linkage 221—224. Latch 219 is, therefore, tripped, and dog 215 is spring-pressed into a position to engage clutch sleeve 218. Since time must be allowed for the taking of a total, notch 217 is located 180 degrees around the periphery of clutch sleeve 218 from the dog 215, and consequently clutch sleeve 218 revolves a half revolution before engagement between the tooth 216 and the notch commences rotation of gear 213. During their period of inactivity the various parts are held in position by means of a spring 206.

Cooperating with gear 213 is a gear 214, mounted on a stub shaft and secured in position by a set screw 214A. By means of this set screw gear 214 can be removed from mesh with gear 213, and its relative position changed by hand. It is in this way that the long feed mechanism may be adjusted, as will be more fully described hereinafter.

The means by which rotation of gears 213 and 214 is converted into a long feed movement consists of two similar trains of driving connections connecting the gears with the drive gear 55 200 of the feed rolls and platen (Figs. 1, 2, and

3). Pivoted respectively to gears 213 and 214 are pitmans 211 and 212, the other ends of each of which are pivoted to plates 207 rotatably mounted on stub shaft 201 on either side of gear 208. The plates 207 each carry a freely mounted pinion 208, constantly in mesh with gear 200 and having a ratchet 209 fixed thereto. Pivotally mounted pawl 210 on each of said plates is spring-pressed into engagement with the ratchets 209.

When, therefore, the gears 213 and 214 are rotated and the respective pitmans 211 and 212 are actuated to oscillate the plates 207 in a counter-clockwise direction, ratchets 209 are held from rotation by pawls 210 and so, too, are the pinions 208. It will be seen that movement of plates 207 in a counter-clockwise direction will cause the gear 200 to rotate in a similar direction, since the pinions 208 will then be locked in engagement therewith. But when gears 213 and 214 have rotated to the extent of effective oscillation of pitmans 211 and 212 in a counter-clockwise direction, upon continued rotation of the gears the pitmans will return in a clockwise direction. The plates will be oscillated in a similar direction, but pawls 210 will ride over ratchets 209 and accordingly pinions 208 will rotate about gear 200.

As has been mentioned before, it is possible to change manually the position of gear 214 relative to gear 213 by loosening and resetting screw 214A, so that effective movement of the driving connection of gear 214 can be varied with relation to the definite effective movement of the driving connection of gear 213. Such effective movement of gear 214 will continue after completion of the effective movement of gear 213, to produce a continuous additional drive of the feed roll mechanism. The pinions 208 are so situated relative to each other (Fig. 3) that counter-clockwise rotation of gear 200 will be at all times continuous.

In this specific instance, then, sheets of paper are fed from a retainer to the initial feed rollers of the long feed mechanism by a sheet picker mechanism. The gear 214 is set to produce the desired length of long feed, and the sheets are conveyed to a printing position on the platen. Whenever it becomes necessary to change the length of the long feed, the gear 214 is again adjusted to produce the proper length of feed.

In Fig. 4 will be seen typical bills 224A and 224B of a utility company. In the first instance the bill was fed to place the first line in printing position, for that customer had a charge for electricity. In the second instance the bill was fed to place the second line in printing position, for that customer did not have a charge for electricity. Such, then, would be an example of a possible use to which an adjustable form feed mechanism might be put.

While I have described what I consider to be a highly desirable embodiment of my invention, it is obvious that many changes in form could be made without departing from the spirit of my invention, and I, therefore, do not limit myself to the exact form herein shown and described, nor to anything less than the whole of my invention as hereinbefore set forth, and as hereinafter claimed.

What I claim as new, and desire to secure by Letters Patent, is:

1. A paper feed mechanism which comprises a platen, a gear associated with said platen and adapted to be driven to advance the platen, a pair of oscillatable members associated with said driven gear, a pair of driving gears, links connected to said respective members and eccentrically connected to said driving gears with differing degrees of eccentricity, and means on the respective members and engaging the periphery of the driven gear to move the driven gear only when the members are moved in a given direction.

2. A paper feed mechanism which comprises a platen, a gear associated with said platen and adapted to be driven to advance the platen, a pair of oscillatable plates associated with said driven gear, a pair of driving gears having the same angular speed, links connected to said respective plates and eccentrically connected to said driving gears with differing degrees of eccentricity, connected ratchets and pinions on said respective plates, said pinions constantly in mesh with the periphery of the driven gear, and pawls on the plates engaging the ratchets to permit movement of the pinions only when the plates are moved in a given direction, one of said driving gears being adjustable to permit the eccentricity of its link to be varied at will.

JOHN MUELLER.
